UNITED STATES PATENT OFFICE.

ALFRED GILLINGHAM AND EDMUND BJORK, OF REGINA BEACH, SASKATCHEWAN,
CANADA.

GRAIN-CAR DOOR FOR BOX CARS.

Application filed September 7, 1927. Serial No. 218,088.

Our invention relates to improvements in grain car doors for box cars, and the object of the invention is to devise a grain door which will be grain tight and yet which will 5 open easily without sticking and will open outward to permit the discharge of grain and will swing inward when not in use so that it may be secured against the inner face of a car wall to enable the car being used 10 for other purposes, and it consists essentially of the arrangement and construction of parts as hereinafter more particularly explained.

Fig. 1 is a perspective view of a portion 15 of a car showing the door frame and our grain door applied thereto and looking from the inside of the car.

Fig. 2 is a similar view to Figure 1 looking from the outside of the car.

Fig. 3 is an enlarged perspective detail of 20 the turnable mounting for the hinge support of one of the door leaves and shown in the closed position.

Fig. 4 is a similar view to Figure 3 showing 25 the parts in the open position.

In the drawing like characters of reference indicate corresponding parts in each figure.

1 indicates the sill of a car, 2 and 3 the up- 30 rights of the door frame and 4 the top plate carried thereby. 5 is the sheeting forming the inside wall of a car body. 6 is a strip of metal extending around the corner formed by each upright 2 and 3 and the sheeting 5 connected thereto and provided centrally with a vertical concaved recess 7 into which the hinge member of the grain door fits as will hereinafter appear so as to make a grain 35 tight joint.

8 and 9 are countersunk plates secured in the sill 1 and provided with cylindrical bosses 10, the upper face of which is cut at an incline from one side to the other as indicated at 11 and provided with a central orifice 12. It will be noted that the bosses 45 10 of the countersunk plates 8 and 9 are inclined in opposite directions, that is, downward towards the door.

13 and 14 are plates secured to the upper 50 timber 15 carried by the top plate 4. 16 are tubular members formed integral with the plates 13 and 14 and depending therefrom in central and vertical alignment with the centre of the orifices 12 of the bosses 10. 17 55 and 18 are the leaves of the grain door which

are provided with engaging rabbeted edges 19 and 20 fitting one within the other to form a grain tight joint. 21 and 22 are cylindrical hinge members formed integral with the door leaves 17 and 18 and fitting the 60 convexed portions 7 of the metal strip 6 above referred to.

The lower ends of the cylindrical hinge members 21 and 22 are cut at an incline as indicated at 23 and 24 corresponding to the incline 11 of the bosses 10. Such lower ends are also provided with central depending pins 25 turnably fitting within the orifices 12. The cylindrical members 21 and 22 extend upward above the leaves 17 and 18 and 70 turnably fit within the depending tubes 16.

It will be noted that the upper edges of the leaves 17 and 18 are slightly below the lower ends of the tube 16 and that therefore when the leaves 17 and 18 are swung inward they 75 are raised from the sill so as to ride above the floor level to the open position thereby opening easily, and at the same time when they are swung in the opposite direction from the open position to the closed they are 80 carried downward so that the lower edges of the leaves are carried into close bearing contact with the upper face of the sill 1 so as to form a grain tight joint.

26 are vertical slots extending through the 85 strips 6 into the vertical members 2 and 3 of the door frame. 27 is a pivoted locking bar swung upon a bolt 28 carried by the leaf 17.

The ends of the bar 27 are bent outward as indicated at 29 so as to extend around 90 the hinge members 21 and 22 into the slots 26 when the bar 27 is swung to a horizontal position. When in this position the bar 27 fits in oppositely set cleats 30 and 31 carried respectively by the leaves 17 and 18 thereby 95 firmly locking the upper portions of the door leaves in position.

A supplemental locking piece 32 is also employed pivoted at 32° so as to swing down at its lower end upon the upper edge of the 100 ends 29 of the locking bar 27 and thereby prevent any danger of such locking bar riding up out of its locking position.

In order to firmly secure the lower portions of the door leaves 17 and 18 tightly 105 together we provide supplemental locking pieces 33 and 34 which are pivotally mounted on each door leaf as indicated at 35 and 36, and when swung down in their locking position assume a criss-cross posi- 110

tion across the joint between the door leaves and fit at their lower ends in slots 37 and 38 formed in the sill 1.

The locking piece 34 is a straight piece 5 and the locking piece 33 is bent as indicated at 33* so as to extend over the piece 34 and fit into the slot 38 which is offset slightly to one side of the slot 37.

When the door leaves are in the open 10 position indicated by dotted lines in Figure 1 the locking pieces 33 and 34 fit into slots 39 and 40 formed in the sill 1 and the upper portions of the door are held by gravity locking pieces 41 which engage the upper 15 edges of the door leaves.

From this description it will be seen that we have devised a grain door for box cars which will be absolutely grain tight and yet which will be easy to open and close, will 20 open outward to permit of the discharge of grain and will close inward when the car is empty against the inner face of the car wall so as to assume a position which will not interfere with the use of the car for any 25 other purpose.

Hooks 42 may be provided which are formed integral with the tubular portion 16 and upon which may be hung any suitable 30 form of closure which will extend between the upper edges of the door leaves 17 and 18 to the top of the car to render the same grain tight if found desirable.

Round knobs or projections 43 and 44 may also be provided so that when the lock-

ing bar 27 is swung to the vertical position 35 which it will assume when the door leaves 17 and 18 are in the open position it is held from rattling, the locking bar being sprung over these knobs into the position indicated by dotted lines in Figure 1. 40

What we claim as our invention is:—

1. In a grain door for box cars, the combination with a door frame including uprights, top plate and sill, of a boss carried by the sill adjacent each upright and having 45 its upper face inclined inward and having a central orifice, a tubular bearing member depending from the top plate in central alignment with each of the aforesaid orifices, door leaves each provided with a cylindrical member extending upward into the tubular bearing members and cut at an incline at their lower ends corresponding to the incline of the aforesaid bosses, and projections extending downward therefrom to 50 turnably fit the orifices of the bosses.

2. In a door locking device, the combination with the door frame having recesses formed in the bottom member at each side of the centre thereof, and a door leaf swung 55 at each side of the opening, of a locking member pivotally mounted to each door leaf in proximity to its free edge and adapted to be criss-crossed so as to extend across the joint between the door leaves into the aforesaid recesses. 60
